Primary Examiner — Patricia A Palasik(74) *Attorney, Agent, or Firm* — Maginot, Moore & Beck
LLP(57) **CLAIM**

The ornamental design for a control device, as shown and described.

DESCRIPTION

FIG. 1 is a perspective view of a control device showing my new design;

FIG. 2 is a left side elevational view of the control device of FIG. 1;

FIG. 3 is a right side elevational view of the control device of FIG. 1;

FIG. 4 is a front elevational view of the control device of FIG. 1;

FIG. 5 is a rear elevational view of the control device of FIG. 1;

FIG. 6 is a top plan view of the control device of FIG. 1; and, FIG. 7 is a bottom plan view of the control device of FIG. 1.

The broken lines in the drawings depict unclaimed environmental subject matter.

1 Claim, 7 Drawing Sheets(56)
